[57] ABSTRACT

A circular drum is circumscribed by an hourglass-shaped sounding member which includes a spacer. One end of the spacer abuts the drum and extends radially outwardly therefrom to a second end which coincides with the periphery of the sounding or resonator member. The drum, sounding member, and a neck are held in assembled relation by a rod which includes two nuts, one at each end, which nuts cooperate with the drum and neck, respectively, with the rod extending through the spacer. A string means is removably secured at one end to the drum and is adjustably secured at the other end to the neck. The tone produced relates to a combination of a banjo and violin or a "country music" type of tone.

STRINGED MUSICAL INSTRUMENT

This invention pertains to a stringed musical instrument and, more particularly, to a combined banjo and violin.

Various types of stringed instruments are known in the art, each producing particular kinds of music and tones. The violin uses stretched strings that produce tones when bowed which are relatively pure and which energize a sound box located between a front and back soundboard. The banjo uses a stretched skin membrane which carries the stretched string support or bridge. Each of these instruments have well-known characteristic tones or sounds. The United States Patent to Newman U.S. Pat. No. 1,297,585 shows a banjo head with a violin-type neck, the instrument of Newman being played with a bow. New types of tones and instruments have been found desirable for music such as country music. The tone also could be described as having a ringing lingering echo effect.

Additionally, it would be convenient to have constructions which can be assembled and disassembled with ease.

One of the objects of the present invention is to provide a combination banjo and violin which has a drum and a sounding member in combination to produce a distinct tone and music when played.

In one aspect, the present invention comprises a membrane drum, a sounding member, and a neck. The sounding member, which circumscribes the drum, includes a spacer which extends radially outwardly from the drum with one end of the spacer abutting the drum. The other end of the spacer coincides with the periphery of the sounding member and abuts one end of the neck. A rod is provided for holding the drum, the spacer and the neck in assembled relation. The rod extends through the spacer and at one end is removably secured to the drum and at the other end is removably secured to the abutting end of the neck. Strings are provided which are removably secured at one end to the drum and fixedly secured at the other end to the far end of the neck.

Other objects, advantages and features of the invention will become apparent from the following description and drawings, which are merely exemplary.

In the drawings:

FIG. 1 shows a side view partially in section of a stringed musical instrument made in accordance with the present invention;

FIG. 2 is a full side view of a stringed musical instrument in accordance with the present invention;

FIG. 3 is a top view of the instrument shown in FIG. 2; and

FIG. 4 shows a sectional view taken along lines 4—4 of FIG. 1.

Referring now to FIGS. 1, 2 and 3, a stringed musical instrument 10 comprising a membrane drum 12, a sounding member 14, and a neck 16 are shown in assembled relation.

Drum 12, which is generally circular in configuration, is seen to include a wooden annular shell 18 (FIG. 4). Overlying shell 18 is a tone ring 20, which is suitably located with respect to shell 18, as by rabbet joint 22. A drum or membrane skin 24 overlies tone ring 20 and is stretched tight by compression rings 26 and 28. First compression ring 26 overlies the periphery of drum skin 24 and second compression ring 28 underlies shell 18 and is suitably located with respect thereto, as by

rabbet joint 30. A plurality of "Allen" screws 32 (only one of which is shown in FIG. 4 for clarity) urge compression rings 26 and 28 together to tightly stretch drum skin 24 over tone ring 20.

Sounding member 14 is hourglass-shaped and includes a first generally circular portion 34 and a second generally circular portion 36 which is integral with first portion 34. First portion 34 is open on one side 38 for accepting drum 12 and first portion 34 is sized so that the periphery of first portion 34 lies in close proximity to drum 12. The sounding member 14 includes a base portion 14A and a removable cover 14B. The cover 14B is removably held on base 14A by suitable screws 14C (FIG. 3). Sounding member 14 also includes a spacer 40 which is enclosed by second portion 36. Sounding member 14 also has a block 41 on the spacer 40.

The first end 42 of spacer 40 abuts the outer periphery of drum 12 and the second end 44 extends to the interior periphery of second portion 36. Spacer 40 extends radially outwardly from drum 12 along or parallel to the diametrical axis 46 of second portion 36.

Neck 16 has a first end 48 which abuts second end 44 of spacer 40. Neck 16 extends radially outward from spacer 40 where it terminates in a second end 50. Neck 16 includes an extension 52 which extends radially inward from first end 48.

A rod 54 holds drum 12, spacer 40 and neck 16 in assembled relation. Rod 54 includes a first nut 56 which is threaded onto first end 58 of rod 54. First nut 56 cooperates with drum 12 at a circumferential location diametrically opposite the location of first end 42 of spacer 40. Rod 54 then extends diametrically across the interior of drum 12 and through spacer 40 and first end 48 of neck 16, where it terminates in a second end 60. Rod 54 also includes a second nut 62 which is threaded into second end 60 of rod 54. Second nut 62 cooperates with first end 48 of neck 16 to hold rod 54 in tension against first nut 56. Those skilled in the art will recognize that rod 54 may be other than the solid, circular cross-section shaft shown without departing from the spirit of the invention.

It should be apparent that the use of a threaded rod and nuts to secure the parts in assembled relation is intended only to be representative of any arrangement wherein first end 58 and second end 60 of rod 54 are removably secured to drum 12 and neck 16, respectively, and the use of any such alternate arrangement will not depart from the spirit of the invention.

A string means 64 includes a plurality of strings 65, a connecting member 66 and a U-shaped bracket 68. The first end of string means 64 is removably secured to drum 12 at a hook 70 which is located at a similar circumferential location to that of nut 56. Each string 65 is secured at its first end to connecting member 66. The ends of U-shaped bracket 68 are secured to connecting member 66 and bracket 68 is placed over hook 70. The second ends of strings 65 are secured to second end 50 of neck 16, as at conventional, tension-adjustable fittings 72.

Drum 12 includes a bridge 74 which cooperates with drum skin 24 and strings 65 to transmit the vibrations of strings 65 to drum skin 24. Extension 52 underlies strings 65 to support them when they are depressed by a musician desiring to play a certain note or a particular string by bowing.

To disassemble instrument 10, the cover screws 14C are removed and neck holding screw 40A is also removed. Cover 14B then can be removed and thereafter the drum, spacer and neck assembly separated from the sounding member 14. Cover 14B is arranged at end 14D (FIG. 3) to overlie the drum so as to hold the parts together when the cover is in place. To disassemble the rest of the instrument parts, nut 62 is removed and rod 54 is unscrewed from nut 56, which may be permanently attached to drum 12 for convenience. Rod 54 is drawn from the position shown and drum 12, spacer 40 and neck 16 can then be separated. Strings 65 are detached from drum 12 by unhooking bracket 68 from hook 70. To reassemble, these steps are repeated in reverse order.

The tone and music produced is the result of the bridge 74 being on the membrane 24, the vibrations of which are heard and are transmitted to the sound box or member 14 which is in the form of a violin-type configuration.

Although only one embodiment of the present invention has been described herein, those skilled in the art will perceive that other modifications can be made without departing from the spirit of the invention except as defined in the appended claims.

What is claimed is:

1. A stringed musical instrument capable of easy disassembly comprising a generally circular drum, a sounding member circumscribing said drum and including a spacer having a first end abutting said drum at a first circumferential location and a second end extending adjacent to the inner wall of said sounding member when assembled therewith and said spacer extending radially outwardly from said drum, a neck having a first end abutting said second end of said spacer and a second end which extends radially outwardly from said spacer, a rod for removably securing said drum, said spacer and said neck in assembled relation, said rod extending through said spacer with a first end removably secured to said drum at a second circumferential location diametrically opposed to said first circumferential location and a second end removably secured to said first end of said neck, and string means having a first end removably secured to said drum at said second circumferential location and a second end secured to said second end of said neck.

2. A stringed musical instrument as claimed in claim 1 wherein said sounding member is violin shaped and further includes a first generally circular portion open on one side for accepting said drum wherein the periphery of said first portion is in close proximity to a portion of the periphery of said drum and second generally circular portion integral with said first portion and enclosing said spacer wherein a diameter of said second portion extends radially outwardly from said drum parallel to said spacer.

3. A stringed musical instrument as claimed in claim 1 wherein said drum includes a wooden annular shell,

a tone ring overlying said annular shell, a drum membrane overlying said tone ring, a first compression ring overlying said drum skin and engaging the periphery thereof, a second compression ring underlying said annular shell, and a plurality of Allen screws for urging said first and second compression rings together to stretch said drum skin over said tone ring.

4. A stringed musical instrument as claimed in claim 1 wherein said neck includes an extension for supporting said strings extending radially inwardly from said first end of said neck and underlying said strings.

5. A stringed musical instrument as claimed in claim 1 wherein said rod includes a first nut threaded onto said first end of said rod and a second nut threaded onto said second end of said rod wherein said first and second nuts cooperate with said drum and said first end of said neck, respectively, to place said rod in tension and hold said drum, and said neck in assembled relation so that disassembly is accomplished by unscrewing said nuts and then removing said rod.

6. A stringed musical instrument as claimed in claim 1 wherein said string means includes a connecting member, a plurality of strings each having a first end secured to said connecting member and a second end adjustably secured to said second end of said neck and a bracket secured at its ends to said connecting member and said drum includes a hook at said second circumferential location for engaging said bracket to removably secure said bracket to said drum.

7. A stringed musical instrument as claimed in claim 6 wherein said drum further includes a drum skin underlying said strings and a bridge cooperating with said drum skin and said strings to transmit vibrations from said strings to said drum skin.

8. A stringed musical instrument as claimed in claim 1 wherein said sounding member includes a base and a removably mounted cover, so that when said cover is removed, the assembly of said drum, spacer and neck can be removed.

9. A stringed musical instrument capable of easy disassembly comprising a generally circular drum, a sounding member circumscribing said drum, spacer means between said drum at a first circumferential location and extending toward the inner wall of said sounding member, said spacer means extending radially outwardly from said drum toward a neck which extends radially outwardly from said spacer means and relative thereto, rod means for removably securing said drum, said spacer means and said neck in assembled relation, said rod means extending through said spacer with a first end removably secured to said drum at a second circumferential location diametrically opposed to said first circumferential location and a second end removably secured to said neck, and string means having a first end removably secured to said drum at said second circumferential location and a second end secured to said second end of said neck.
